PORTABLE CONTAINER AND VALVE
THEREFOR

Daniel Mapes, West Caldwell, N. J., assignor to
Specialties Development Corporation, Bloom-
field, N. J., a corporation of New Jersey

Application April 24, 1943, Serial No. 484,395

7 Claims. (Cl. 222—3)

The present invention relates to valves, and more particularly to valves for portable containers adapted to contain high pressure fluid media.

An object of the present invention is to provide a valve of the foregoing character having an operating handle which may be readily manipulated to operate the valve.

Another object of the invention is to provide a high pressure fluid media container having a valve secured thereto which is provided with a carrying handle and a valve operating handle operatively associated with each other to facilitate discharging the contents of the container while carrying the same.

Another object is to provide a valve of the foregoing character having means for effecting latching of the operating handle in valve operating position in a simple and expeditious manner.

Another object is to provide a valve of the foregoing character which is simple and sturdy in construction and comprises a minimum number of parts which are readily manufactured and assembled.

A further object consists in the construction and arrangement of parts, whereby the foregoing objects may be accomplished.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming a part of the specification, wherein:

Figure 1 is a sectional view of a valve attached to a portable high pressure fluid media container (partly shown), illustrating an embodiment of the invention.

Figure 2 is a fragmentary sectional view of a modified latching arrangement.

Referring more particularly to Figure 1 of the drawing, there is shown a container, such as a portable cylinder 10 adapted to contain high pressure fluid media, for example, liquified carbon dioxide adapted to be used for fire extinguishing purposes or the like. The cylinder is provided with a neck 11 having a threaded opening therein adapted to receive a valve 12, about to be described.

The valve comprises a valve body 14 having a threaded plug-shaped portion 15 adapted to be

threadedly secured into the opening or outlet of the cylinder. The valve body is formed with a passage 16 extending therethrough. One end of the passage 16 extends through the plug-shaped portion 15 and preferably communicates with a siphon tube 17 which is secured to the plug-shaped portion 15 and extends into the cylinder. The other end of the passage 16 communicates with an outlet 18 to which a suitable shield or horn (not shown) may be connected for effecting discharge of the fluid media from the cylinder.

A valve chamber 20 is provided in the passage 16 between the respective ends thereof which is formed with a valve seat 21 upon which a valve member or disc 22 is adapted to be seated by means of a suitable spring 24 or the like. The valve member 22 is adapted to be unseated by one end of a suitable pin or rod 25 slidably mounted in the valve body and extending through a suitable packing or gasket 26. The other end of the pin 25 extends outwardly of the valve body and is adapted to be engaged by an operating handle 27 or the like, described hereinafter.

In order to readily facilitate lifting and carrying the cylinder to which the valve is secured, an elongated carrying handle 29 is provided which has one end thereof attached to the valve body, and extending outwardly thereof. The handle 29 may be pivotally mounted between a pair of lugs or ears 30 (one shown) formed with the valve body by means of a pin 31 supported by the lugs 30. With this arrangement the handle 29 may be swung downwardly against the cylinder when not in use and may be swung upwardly when the cylinder is to be lifted or carried. Intermediate its ends, the handle 29 is provided with an aperture or recess 32 formed with an undercut or shoulder 34, the function 40 of which will be described hereinafter.

The operating handle 27 referred to herein has one end thereof pivotally attached to the valve body. This may be accomplished by mounting the handle 27 on a pin 35 supported by a pair of lugs or ears 36 (one shown) formed with the valve body above the lugs or ears 30. Adjacent its pivotally mounted end, the handle 27 is provided with a cam portion 37, or the like, adapted to engage and move the slidable pin or rod 25 to effect unseating of the valve member 22.

The operating handle 27 extends outwardly of the valve body and is positioned above and adjacent the carrying handle 29, as illustrated herein, so that it may be readily pressed downwardly toward the carrying handle to operate the valve.

In accordance with the invention, it is desired to lock the operating handle in valve operating position to maintain the valve member 22 unseated. This may be accomplished by a suitable latching device associated with the handles. For example, the operating handle may have a latching member 40 pivotally supported thereon which extends through an aperture or recess 41 formed in the handle 27. The lower end of the latching member 40 is formed with a latching projection 42 adapted to extend into the aperture 32 of the carrying handle 29 and adapted to engage the undercut or shoulder 34 (as shown in broken lines) to thereby link the operating handle 27 in latched relation to the carrying handle 29 in the downwardly pressed operating position of the operating handle.

A spring 45, under tension, having one end connected to the latching member above its pivot and having its other end connected to the operating handle, may be provided for urging the projection 42 into engagement with the undercut or shoulder 34. The upper end of the latching member 40, projects above the operating handle 27 and is provided with a knurled portion 46 adapted to be engaged and pushed by the thumb of the hand grasping the handles to thereby effect disengagement of the latch.

In Figure 2 a modified latching arrangement is illustrated which comprises a substantially horizontal lug, ear, or extension 50 formed with the valve body and having an aperture 32' extending therethrough which is provided with an undercut or shoulder 34' adapted to be engaged by the latching projection 42 of the latching member 40.

In operation, the underside of the carrying handle 29 is grasped by the fingers of one hand and pressure is exerted on the upper side of the operating handle 27 by the palm of the hand to move the operating handle downwardly toward the carrying handle. As this is being done the lower end of the latching member 40 moves downwardly in the aperture 32 (Figure 1) or 32' (Figure 2) and the latching projection 42 thereon is urged into engagement with the undercut 34 (Figure 1) or 34' (Figure 2) by the action of the spring 45. This effects latching the operating handle and maintains it in a position to cause the valve member 22 to be held unseated to permit the fluid media to be discharged from the cylinder.

When it is desired to permit the valve member 22 to reseat and stop the discharge of the fluid media, the portion 46 is pushed toward the valve body in opposition to the spring 45 by the thumb of the hand grasping the handles 27 and 29. Disengagement of the latch is thus effected, permitting the operating handle to be raised to its initial position.

From the foregoing description it will be seen that the present invention provides an improved valve for portable containers of high pressure fluid media or the like. With the arrangement illustrated herein, the container and the valve constitute a portable self-contained unit which can be readily lifted or carried and the valve can be readily operated by an ordinary full hand squeezing action, while in the carrying position, to distribute the fluid medium over wide areas. This leaves the other hand free to manipulate the discharge horn or, while the fluid discharge is stopped, to be employed for other purposes. The valve is rugged in construction and can readily withstand any rough usage to which it may be subjected.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

It is also to be understood that the following claims are intended to cover all the generic and specific features of the invention herein described, and all statements of the scope of the invention which, as a matter of language, might be said to fall therebetween.

I claim:

15. A valve construction comprising a valve body having a passage extending therethrough and having a valve seat in said passage; a valve member for said valve seat; an axially slideable operating stem mounted in said valve body for effecting unseating of said valve member and provided with an exposed end; said valve body provided with a member extending outwardly therefrom and equipped with a shoulder; an operating member pivotally mounted on said valve body and in proximity to said exposed end of said stem; said operating member extending outwardly from said valve body above said first mentioned member and being formed, adjacent said exposed end, with an end face confronting said exposed end and slidably engageable with said exposed end for axially operating said stem when said operating member is grasped manually and squeezed downwardly towards said first mentioned member; a latching member pivotally mounted on said operating member and having a latching projection at one end thereof for latching engagement with said shoulder; and a spring carried by said operating member for urging said latching projection into engagement with said shoulder; said latching member having a manually engageable portion at its other end for effecting release of said projection from said shoulder, in opposition to said spring.
20. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full hand squeezing action while in a carrying position, and means responsive to said squeezing action for releasably latching said opening means in position to maintain said passage open.
25. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full
30. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full
35. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full
40. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full
45. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full
50. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full
55. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full
60. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full
65. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full
70. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full
75. A portable self-contained unit for dispensing a high pressure fluid medium over wide areas during carrying of the unit, said unit comprising a container for the fluid medium, a housing secured to said container and provided with a fluid passage extending from said container to a discharge outlet, means in said housing normally closing said passage, means for affecting said closing means to open said passage, means including a pair of handles of shape, size and relation to each other constituting them substantially as a single hand fitting structure for carrying the unit and for operating said opening means to open said passage in response to ordinary full

hand squeezing action while in a carrying position, and means cooperating between the handles and responsive to said squeezing action for releasably latching said opening means in position to maintain said passage open.

4. A valve structure for assembly with a portable container, comprising a valve body having a passage therethrough, a valve seat in said passage, a valve member for the seat, a valve stem for unseating said valve member, a carrying handle and a valve operating handle for actuating said stem and movably mounted relative to each other on the valve body and projecting outwardly from the latter, said valve operating handle being responsive to hand squeezing action between the handles for actuating said valve operating handle, and releasable latching means including a pivotally mounted latch element disposed between the handles and operative as a link to hold the valve operating handle in position maintaining the valve member off the valve seat.

5. A valve structure for assembly with a portable container, comprising a valve body having a passage therethrough, a valve seat in said passage, a valve member for the seat, a valve stem for unseating said valve member, a carrying handle and a valve operating handle for actuating said stem and movably mounted relative to each other on the valve body and projecting outwardly from the latter, said valve operating handle being responsive to hand squeezing action between the handles for actuating said valve operating handle, and releasable latching means including a pivotally mounted latch element operative as a link between the handles to hold the valve operating handle in position maintaining the valve member off the valve seat.

6. A valve structure for assembly with a portable container, comprising a valve body having a passage therethrough, a valve seat in said passage, a valve member for the seat, a valve stem for unseating said valve member, a carrying handle and a valve operating handle for actuating

said stem, both handles being mounted on the valve body and projecting from the latter, said valve operating handle being pivotally mounted with respect to the valve body and being responsive to hand squeezing action between the handles for effecting actuation of said stem to unseat said valve member, and releasable latching means including a pivotally mounted latch element operative as a link between the handles to hold the valve operating handle in position maintaining the valve member off the valve seat.

5. A valve structure for assembly with a portable container, comprising a valve body having a passage therethrough, a valve seat in said passage, a valve member for the seat, a valve stem for unseating said valve member, a carrying handle and a valve operating handle for actuating said stem and movably mounted relative to each other on the valve body and projecting outwardly from the latter, said valve operating handle being responsive to hand squeezing action between the handles for effecting actuation of said stem to unseat said valve member, and releasable latching means including a pivotally mounted latch element operative as a link between the handles to hold the valve operating handle in position maintaining the valve member off the valve seat.

10. A valve structure for assembly with a portable container, comprising a valve body having a passage therethrough, a valve seat in said passage, a valve member for the seat, a valve stem for unseating said valve member, a carrying handle and a valve operating handle for actuating

15. A valve structure for assembly with a portable container, comprising a valve body having a passage therethrough, a valve seat in said passage, a valve member for the seat, a valve stem for unseating said valve member, a carrying handle and a valve operating handle for actuating

20. A valve structure for assembly with a portable container, comprising a valve body having a passage therethrough, a valve seat in said passage, a valve member for the seat, a valve stem for unseating said valve member, a carrying handle and a valve operating handle for actuating

25. A valve structure for assembly with a portable container, comprising a valve body having a passage therethrough, a valve seat in said passage, a valve member for the seat, a valve stem for unseating said valve member, a carrying handle and a valve operating handle for actuating

30. A valve structure for assembly with a portable container, comprising a valve body having a passage therethrough, a valve seat in said passage, a valve member for the seat, a valve stem for unseating said valve member, a carrying handle and a valve operating handle for actuating

35. A valve structure for assembly with a portable container, comprising a valve body having a passage therethrough, a valve seat in said passage, a valve member for the seat, a valve stem for unseating said valve member, a carrying handle and a valve operating handle for actuating

40. A valve structure for assembly with a portable container, comprising a valve body having a passage therethrough, a valve seat in said passage, a valve member for the seat, a valve stem for unseating said valve member, a carrying handle and a valve operating handle for actuating
